(57) **CLAIM**
I claim the ornamental design for a lid and seal for container, as shown and described.

DESCRIPTION

FIG. 1 is a front perspective view, from above, of the claimed design;

FIG. 2 is a rear perspective view, from beneath, of the claimed design;

FIG. 3 is an exploded front perspective view, from above, of the claimed design, showing the lid component and seal components separated;

FIG. 4 is an exploded rear perspective view, from beneath, of the claimed design, showing the lid component and seal components separated;

FIG. 5 is a top plan view of the lid component of the claimed design;

FIG. 6 is an underneath plan view of the lid component of the claimed design;

FIG. 7 is a top plan view of the seal component of the claimed design;

FIG. 8 is an underneath plan view of the seal component of the claimed design;

FIG. 9 is a left or right side view of the lid component of the claimed design. The left side view is the same as the right side view;

FIG. 10 is an end view of the lid component of the claimed design. Both end views are the same;

FIG. 11 is a left or right side view of the seal component of the claimed design. The left side view is the same as the right side view; and,

FIG. 12 is an end view of the seal component of the claimed design. Both end views are the same.

The purpose of broken lines in the drawing is to illustrate an optional vent that forms no part of the design to be patented. The claimed design is the lid and seal, in combination.
